ELECTRICAL PLAY CONTROL MECHANISM

Jerald D. Weaver, Fort Wayne, Ind., assignor to
 Farnsworth Television and Radio Corporation,
 a corporation of Delaware

Application January 23, 1942, Serial No. 427,906

8 Claims. (Cl. 274—10)

This invention relates to an automatic phonograph and more particularly to improved control apparatus which is operable to control the playing of a plurality of records on one side or on both sides.

The object of the present invention is to provide an improved electrical control mechanism for an automatic phonograph which will permit an operator to control, at any time, the playing of a plurality of records on one side or on both sides.

Another object of the present invention is to provide an improved electrical control mechanism for an automatic phonograph which will permit an operator to pre-select which records of a group of records shall be played on one side and which shall be played on both sides.

A further object of the present invention is to provide an improved electrical control mechanism for an automatic phonograph for controlling the playing of a plurality of records, the setting of which can be changed without affecting the normal playing of the phonograph.

In accordance with the present invention, there is provided an automatic phonograph adapted to play one side or both sides of a plurality of records. The phonograph includes an actuating means movable after the playing of one side of a record. The actuating means has a first adjustment for effecting the playing of a record on both sides and a second adjustment for effecting the playing of a record on one side. The phonograph also includes a plurality of control members adapted for independent predetermined adjustments. An electric circuit is associated with the control members to be energized thereby. The electric circuit includes electrical means which is adapted to be operably associated with the actuating means in response to the energization of the electric circuit. Means are also provided for effecting the cooperation of the electric circuit with the control members whereby the predetermined adjustments of the control members will effect the adjustment of the actuating means to the first and second adjustments for successively and automatically playing a plurality of records on one side or on both sides, according to the adjustments of the control members.

For a better understanding of the invention, together with other and further objects thereof, reference is had to the following description, taken in connection with the accompanying drawings, and its scope will be pointed out in the appended claims.

In the accompanying drawings:

Fig. 1 is a side elevation view showing a complete assembly of one embodiment of the play-control apparatus;

5 Fig. 2 is a top plan view of the control dial;

Fig. 3 is a section on line 3—3 of Fig. 1;

Fig. 4 is an end elevation view partly in section showing the plurality of control members;

Fig. 5 is a section on line 5—5 of Fig. 3;

Fig. 6 is a section on line 6—6 of Fig. 4;

Fig. 7 is a section on line 7—7 of Fig. 1; and

Fig. 8 is a section on line 8—8 of Fig. 1.

Fig. 9 is a top plan view of a second embodiment of the play control apparatus in accordance with the invention;

Fig. 10 is a cross-section taken on line 10—10 of Fig. 9;

Fig. 11 is a cross-section taken on line 11—11 of Fig. 10;

20 Fig. 12 is a cross-section taken on line 12—12 of Fig. 10;

Fig. 13 is a cross-section taken on line 13—13 of Fig. 10.

Referring now more particularly to Fig. 1 of 25 the drawings, the entire apparatus is mounted on a base plate 10. Beneath the base plate 10, there is suspended a bracket 11 which supports a rotatable drive shaft 12. The shaft 12 may be driven in any suitable manner known in the art. 30 For example, it may be driven in the same manner that shaft 61 is shown to be driven in United States Patent No. 2,012,185. A tripping mechanism, such as that shown in United States Patent No. 2,018,881, may be incorporated to initiate the 35 rotation of the shaft 12 after the playing of one side of a record by the phonograph.

A cam means 13, preferably in the form of a cam wheel, is mounted on the shaft 12 to rotate therewith. On the periphery of the cam wheel 40 13 (Figs. 1 and 3), there are provided the cam elements 14 and 15—15. Between the cam elements 15—15, there is provided an adjustable member 16 which is biased in the position shown in Fig. 3 by a spring 17. The adjustable member 45 16 is adapted to be moved in a clockwise direction (Fig. 3) in response to a force sufficient to overcome the biasing force of the spring 17.

The cam wheel 13 is also provided with a substantially concentric cam groove 18, two angular cam grooves 19 and 20 and two other cam grooves 21 and 22. The cam grooves 18—22 form first and second cam paths, as is clearly shown in Fig. 1. A switching element 23 (see Figs. 1 and 8) is pivotally mounted in a suitable manner on the cam wheel 13, preferably in the 50 55

common area between the cam grooves 21 and 22. The switching element 23 is provided with a pin or extension 24 which is adapted to move in a slot 25 formed in the cam wheel 13. The pin 24 is adapted to move in the slot 25 as the switching element 23 is pivoted from the full-line position to the dotted-line position shown in Fig. 1. The switching element 23 has formed thereon a toe 26 and heel portions 27 and 28. The purpose of the switching element 23 is to open and close the entrance to the cam grooves 21 and 22, in a manner to be described hereafter.

A pin 29 on a movable member 30 is adapted to cooperate with the cam grooves 18-22, while the cam wheel 13 is rotating. If the switching element 23 is in the dotted-line position shown in Fig. 1, while the cam wheel 13 is rotating through a cycle of operation, the pin 29 will move in the cam grooves 18, 19, 22 and 20, which is the second cam path referred to above. If the switching element 23 is in the full-line position shown in Fig. 1, while the cam wheel 13 is rotating through a cycle of operation, the pin 29 will follow the cam grooves 18, 19, 21 and 20, which cam grooves describe the first cam path referred to above. While the pin 29 is in the groove 22, it engages the heel 28 to move the switching element 23 from the dotted-line to the full-line position shown in Fig. 1. While the pin 28 is in the groove 21, it engages the heel 27 to move the switching element 23 from the full-line to the dotted-line position shown in Fig. 1. The movable member 30 and the cam wheel 13 are adaptable to cooperate with the record-reversing mechanism and the record-changing mechanism described in United States Patent No. 2,012,185 to carry out record-reversing and record-changing cycles, respectively.

A lever or connecting member 31 is pivotally supported in a suitable manner preferably on an arm 32 provided on the bracket 41 (Figs. 1 and 3). On one end of the lever 31, there is provided a pin 33 which is maintained in the path of the cam elements 15-15 and the adjustable member 16, while the lever 31 is maintained in its normal position shown by dotted lines in Fig. 3. A member 34 is pivotally mounted on the opposite end of the lever 31 and is biased by a spring 35 into engagement with an ear 36 provided on the lever 31, as shown in Fig. 3. The member 34 is adapted to be moved in a clockwise direction from the position shown in Fig. 3 against the biasing action of the spring 35. The free end of the member 34 has a toothed portion 37. A spring 38, one end of which is fixed to the lever 31 and the other end of which is fixed to a suitable body, normally maintains the lever 31 against a pin 39 provided on a suitable fixed object, such as a bracket 40 (Fig. 3).

The lever 31 is adapted to cooperate with control mechanism for controlling the playing of a plurality of records on one side or on both sides. One embodiment (Figs. 1-4) includes a member or shaft 41 movably mounted on a bracket 42, preferably in the manner shown in Fig. 4. The member 41 extends upwardly from the bracket 42 and through an opening in the base plate 10, as shown in Figs. 1 and 4.

At the lower end of the member 41, there is provided a plate or a gear 43 which is rotatable with the member 41. The gear 43 has a plurality of perforations annularly spaced near its periphery, as shown in Fig. 3. The gear 43 is positioned to be engaged at its periphery by the pivotal member 34 movable with the lever 31.

When the lever 31 is rotated in a clockwise direction (Fig. 3), it transmits counterclockwise movement (Fig. 3) to the gear 43. Below the gear 43, there is provided a ratchet wheel 44 (Figs. 4 and 6) which also is rotatable with the member 41. A spring-biased pawl 45 is adapted to engage the ratchet wheel 44 for preventing the clockwise movement of the member 41. Near the opposite end of the member 41, there is affixed thereto in a suitable manner a plate 46 (Figs. 1, 2 and 4) which is perforated in the same manner as the gear 43. The upper end of the member 41 is provided with a manual control knob 47 to enable an operator to rotate the member 41 and therewith the plates 43 and 46 for settling the play-control mechanism. A plurality of control members 48, preferably in the form shown in Figs. 1 and 4, are frictionally mounted in the perforations of the plates 43 and 46 and extend above the plate 46 and below the plate 43, as shown in Fig. 1. The control members 48 are manually adjustable in a vertical plane relative to the plates 43 and 46 to two different positions. The uppermost position of the control members 48 will be referred to as a first position, and the lowermost position of the control members will be referred to as a second position. When the control members 48 are in the second position and they move past a pin 49 fixed to the bracket 42, the control members 48 are moved back, automatically, to the first position. The control members 48 are also movable in unison with the members 41, 43 and 46 in a horizontal plane. The movement of the control members 48 in a horizontal plane moves them successively past a pointer 50, shown in Fig. 2.

An intercepting mechanism is associated with the control mechanism, just described, the connecting member 31 and the switching element 23 to cooperate in carrying out the play-control operation. This intercepting mechanism is best shown in Figs. 1 and 2 and includes an electric circuit. In the electric circuit, there are provided a movable contact 51 and a fixed contact 52 which are mounted on the bracket 42 by the insulating means 53. The movable contact 51 is positioned in the path of the plurality of control members 48 which are in the second position and is moved into engagement with the contact 52 as these control members, in the second position, are successively moved into engagement with the movable contact 51.

A lead 54 connects the movable contact 51 to a source of supply. A lead 55 connects the fixed contact 52 to a solenoid 56 having a movable armature 57. The solenoid 56 is supported on the bracket 40, preferably in the manner shown in Fig. 7. The bracket 40 is fixed, in a suitable manner, to the bottom of the base plate 10. A lead 58 connects the solenoid 56 to a movable contact 59 which is associated with a contact 60. Contacts 59 and 60 are supported by insulating means 61 provided on the bracket 40. The movable contact 59 is positioned in the path of the cam portion 14 on the cam wheel 13 and, when the cam portion 14 is moved past the movable contact 59, it moves the contact 59 into engagement with the contact 60. A lead 62 connects the contact 60 to the source of supply.

One end of the armature 57 is associated with a U-shaped member 63 having the legs 64 and 65. The member 63 is pivotally mounted on the bracket 40, preferably in the manner shown in Fig. 7. The leg 64 of the member 63 normally rests on top of the armature 57 and is adapted

to be raised from the full-line position to the dotted-line position shown in Fig. 7 when the solenoid 56 is energized. When the leg 64 is raised by the upper end of the armature 57, the leg 65 is moved out of the path of the lever 31.

As has been previously described, the lever 31, which is normally maintained by the spring 38 in the dotted-line position shown in Fig. 3, is adapted to cooperate with the gear 43 and the cam elements 15-15 and 16. While the cam wheel 13 is rotating through a cycle of operation, one of the cam elements 15 engages the pin 33 on the lever 31 and begins to pivot the lever 31 in a clockwise direction (Fig. 3) against the biasing action of the spring 38. The continued movement of the cam wheel 13 brings the adjustable cam member 16 into engagement with the pin 33 (Fig. 3). If the leg 65 is in the path of the lever 31, the movement of lever 31 is stopped when it reaches a position midway between the dotted-line and the full-line positions shown in Fig. 3. The stopping of the lever 31 by the leg 65 forces the adjustable member 16 to pivot in a clockwise direction (Fig. 3) against the biasing action of the spring 17. If the leg 65 is out of the path of the lever 31, the adjustable member 16 is maintained in its normal position by the spring 17 and moves the lever 31 in a clockwise direction to the full-line position shown in Fig. 3. The shape of the members 15-15 and 16 are such that, after the lever 31 is in the full-line position shown in Fig. 3, or in the midway position previously mentioned, the adjustable member 16 and one of the cam elements 15 permits the spring 38 to move the lever 31 back to the dotted-line position (Fig. 3). The clockwise movement (Fig. 3) of the lever 31 brings the toothed portion 37 of the member 34 into engagement with the gear 43 and rotates it in a counterclockwise direction (Fig. 3). If the lever 31 is moved the full distance from the dotted-line to the full-line positions shown in Fig. 3, the gear 43 and the plate 46 are moved the distance between adjacent numbers on plate 46 (see Fig. 2). If the lever 31 is moved only half the distance between the dotted-line and full-line positions shown in Fig. 3, the gear 43 and the plate 46 are moved only half the distance between adjacent numbers on the plate 46. On the return movement of the lever 31 to its normal dotted-line position (Fig. 3), no movement is transmitted to the gear 43. This is true because of the manner in which the member 34 is connected to the lever 31 and because the ratchet mechanism, including the members 33 and 45 prevents the rotation of the gear 43 in a clockwise direction (Fig. 3).

The lower end of the armature 57 (Fig. 1) is connected to one end of a lever 66 which is pivotally mounted intermediate its ends to the bracket 40. When the solenoid 56 is energized and the armature 57 is moved upwardly during a cycle of operation of the cam wheel 13, the lever 66 is pivoted in a clockwise direction (Fig. 1). If the switching element 23 is in the full-line position shown in Fig. 1, the clockwise movement of the lever 66 positions its free end for moving the switching element 23 into the dotted-line position (Fig. 1).

Another embodiment of the control mechanism, which is adapted to operate with the lever 31 and the first intercepting mechanism described above, is shown in Figs. 9-13 and will be described now.

This embodiment of the control mechanism includes a pair of brackets 74-74 supported in a

suitable manner beneath the base plate 10. A plate 75 is connected to the brackets 74-74, preferably in the manner shown in Fig. 10. The plate 75 has a plurality of perforations annularly spaced near its periphery, in which are frictionally mounted a plurality of control members 76 to move from an uppermost to a lowermost position relative to the plate 75. When the control members 76 are in their uppermost position, they will be referred to as being in a first position, and when they are in their lowermost position, they will be referred to as being in a second position. A plate 77 of insulating material is connected to the brackets 74-74 below the plate 75. An annular member 78 (see Fig. 11) is provided on the top surface of the plate 77. This member is of electrical conductive material and has an ear 79 extending downwardly through an opening 80 in the plate 77. The ear 79 is connected to the line 55 of the electric circuit previously described. A bracket 81 is connected in a suitable manner to the bottom of the plate 77. A shaft 82 is connected to the bracket 81 to rotate relative thereto and extends upwardly through openings in the plates 77, 75 and 10, as shown in Fig. 10. The upper end of the shaft 82 is provided with a control knob 83, by which an operator may rotate the shaft 82 in a counterclockwise direction (Fig. 9) to set the play-control mechanism. Intermediate the ends of the shaft 82, there is affixed thereto in a suitable manner, as shown in Fig. 10, an insulating member 85 in the form of a sleeve. The member 85 preferably has a reduced portion 86 at the lower end thereof and is provided with notches 87-87 and 88 (see Fig. 11). A member 89, having an annular portion 90, an extending portion 91 and a contact 92, is mounted on the reduced portion 86 of the member 85 to rotate around the axis of the shaft 82. A pair of ears 93-93, extending upwardly from the annular portion 90 of the member 89, is adapted to extend into the notches 87-87. This mounting of the member 89 permits it to rotate with the shaft 82. The contact 92 on the member 89 is adapted to be moved into contact with the annular member 78 when one of the control members 76 in the second position engages the contact 92. A member 94, having a turned-up end 95, is slipped over the reduced portion 86 in the manner shown in Fig. 10. An ear 97 on the member 94 extends into the notch 88 of the member 85 and permits the member 94 to move with the member 85 and the shaft 82. As the free end 95 of the member 94 (see Fig. 12) moves past the control members 76 in the second position, it elevates them to their first position. In this manner, after the control members in the second position have served their function, they are automatically moved to their first position. An annular member 98 is on the reduced portion 86 under the annular portion of the member 94. The annular member 98 is provided with an ear 99 which extends through an opening in the plate 77 and is connected to the line 54 of the electric circuit previously described. An annular insulating member 100 is mounted on the shaft 82 below the reduced portion 86 of the member 85. Thus, it is seen that the members 89, 94 and 98 are completely insulated from the shaft 82 and any other metal or electrical conducting materials.

At the lower end of the shaft 82, there is fixed thereto a gear 101, whose periphery is adapted to be engaged by the member 34 on the connecting member 31, previously described. Below the gear 101, a ratchet wheel 102 is fixed to the shaft 82

to rotate therewith. A spring-biased pawl 103, suitably connected to the bracket 81, is adapted to engage the ratchet wheel 102 for preventing the rotation of the shaft 82 in a clockwise direction.

From the description of this embodiment of the control mechanism, it is seen that the connecting member 31, by means of the member 34, is adapted to rotate the gear 101 and the member 89 in a counterclockwise direction. This movement of the member 89 successively brings the contact 92 into engagement with the control members in the second position for carrying out the play-control operation.

In order that the play-control mechanism functions properly, it is evident from the description of the invention that the switching element 23 must be in the full-line position shown in Fig. 1 before the phonograph is initiated for operation. If the switching element 23 is not in the full-line position (Fig. 1), it may be moved into such position by mechanism shown in Figs. 1 and 8. This mechanism includes a spring-biased rod 105 mounted on the bracket 40 in the manner shown in Fig. 1. The upper end of the rod 105 extends above the base plate 10 and has a knob 106 provided thereon. The lower end of the rod 105 is adapted to be brought into engagement with an L-shaped member 107 pivotally mounted on the bottom of the bracket 40. The legs of the member 107 are counterbalanced so that the member 107 normally is in the full-line position shown in Fig. 1. The member 107 is movable in a counterclockwise direction from this position by pressing the rod 105 downwardly against the force of its biasing spring. When the lever 107 is pivoted in a counterclockwise direction from the full-line position to the dotted-line position shown in Fig. 1, one end of the member 107 moves upwardly. If the switching element 23 is in the dotted-line position shown in Fig. 1, then the member 107 engages the pin 24 and moves the switching element to the full-line position shown in the same figure. After the member 107 has moved the switching element 23 to the full-line position (Fig. 1) and the lever 105 has been released to its normal position, the member 107, as a result of its counterbalance, moves back to its normal position, as shown in Fig. 1.

Mode of operation

The mode of operation of applicant's invention will now be described. Before setting into operation an automatic phonograph in which applicant's invention is incorporated, the rod 105 is pressed downwardly to move the switching element 23 to its full-line position shown in Fig. 1, and a plurality of records are placed in the phonograph. Thereafter, the knob 47 is rotated in a counterclockwise direction until the control member 48 opposite No. 1 on the plate 46 is opposite the pointer 50 in Fig. 2. As has been previously described, each one of the control members 48 controls the playing of a corresponding record in the automatic phonograph. After the control members 48 are set relative to the pointer 50, the operator presses into the second position the control members 48 corresponding to records which he wants to play only on one side and leaves in the first position the control members 48 corresponding to records which he wants to play on both sides.

In this mode of operation, it will be assumed that the control members 48 opposite the Nos. 1, 3 and 4 (Fig. 2) are in the first position and that

the control members opposite Nos. 2 and 5 are in the second position.

With the play-control mechanism in the assumed position, the control member 48 opposite No. 1 (Fig. 2) will be above the contact 51 but out of engagement with it, and the leg 65 will be in the path of the lever 31 (Fig. 7).

After the first record is played on one side, the tripping mechanism previously referred to initiates the rotation of the cam wheel 13 through a cycle of operation. The first operation which is performed by the cam wheel 13 is to close the contacts 59 and 60. This is brought about by the cam portion 14 moving the contact 59 into engagement with the contact 60. However, since the contacts 43 and 51 are open, the electromagnet 56 is not actuated. This leaves the leg 65 in the path of the lever 31 and the lever 66 remains out of the path of the pin 24 on the switching element 23.

As is clear from the description, the switching element 23 will be in the full-line position (Fig. 1) during this cycle of operation of the cam wheel 13. With the switching element 23 in this position, the member 30 is guided over the path formed by the grooves 18, 19, 21 and 20 so that the member 30 cooperates with record-reversing mechanism to turn over record No. 1 on the turntable. One form of mechanism for accomplishing this function is described in United States Patent No. 2,012,185. When the pin 29 of the member 30 engages the heel 27 during its movement in the cam groove 21, it moves the switching element 23 from the full-line position to the dotted-line position shown in Fig. 1.

While the cam portion 14 is in engagement with the contact 59, the forward cam element 15 (see Fig. 1) moves into engagement with the pin 33 and begins to pivot the lever 31 in a clockwise direction (Fig. 3). The continued movement of the cam wheel 13 brings the adjustable cam member 16 into engagement with the pin 33 and the lever 31 is moved further in a clockwise direction (Fig. 3). When the lever 31 has moved half the distance between the dotted-line position and the full-line position shown in Fig. 3, it is stopped by the leg 65. The stopping of the lever 31 by the leg 65 forces the member 16 to move in a clockwise direction (Fig. 3) against the biasing action of the spring 17.

During the clockwise movement (Fig. 3) of the lever 31, just referred to, the member 34 engages the gear 43 and moves it, the shaft 41 and the plate 46 in a counterclockwise direction (Fig. 3) 55 a distance midway between the control members 48 at No. 1 and No. 2 in Fig. 2.

As the cam wheel 13 continues to rotate, the member 16 and the second cam element 15 are moved out of the path of the pin 33 and permit the spring 38 to move the lever 31 in a counterclockwise direction (Fig. 3) to its normal dotted-line position (Fig. 3). As is clear from the description, the ratchet mechanism shown in Fig. 6 prevents the counterclockwise movement of the lever 31 from transmitting motion to the gear 43. Thereafter, the cam wheel 13 finishes its cycle of rotation and the phonograph is ready to reproduce the opposite side of record No. 1.

After the opposite side of record No. 1 is reproduced, the tripping mechanism again initiates the rotation of the cam wheel 13. Since, during this cycle of operation of the cam wheel 13, the contacts 51 and 52 will again remain out of engagement with each other, the play-control mechanism will function in the same manner as it

did during the previous cycle. During this cycle, the plate 46 is moved to position the control member 48 opposite No. 2 (Fig. 2) opposite the pointer 50 after the cam portion 14 has moved into and out of engagement with the contact 59. With the control member 48 opposite No. 2 in this position, it will be in engagement with the contact 51 and hold it in engagement with the contact 52 until the gear 43 is again moved by the lever 31. Also, during this cycle of operation, it will be evident that the pin 29 of the member 30 is guided by the grooves 18, 19, 22 and 20 or the second cam path to move the member 30 to cooperate with the record-moving mechanism for changing a record on the turntable. One embodiment of such mechanism is described in United States Patent No. 2,012,185. As the pin 29 moves in the cam groove 22, it engages the heel 28 to move the switching element 23 from its dotted-line to its full-line position shown in Fig. 1.

After one side of record No. 2 is reproduced, the tripping mechanism again initiates a cycle of operation of the cam wheel 13. During this cycle, when the cam portion 14 moves the contact 59 into engagement with the contact 60, the electric circuit to the electromagnet 56 is closed and the electromagnet 56 is actuated to move the leg 65 out of the path of the lever 31 and to move the lever 66 for positioning the switching element 23 into the dotted-line position shown in Fig. 2. As the cam wheel 13 continues to rotate, the pin 24 moves into engagement with the lever 66, whereby the switching element 23 is moved from the full-line position to the dotted-line position shown in Fig. 1. With the switching element 23 in this position, the member 30 again is permitted to follow the second path formed by the cam grooves 18, 19, 22 and 20. This again permits the member 30 to cooperate with record-moving mechanism for changing a record on the turntable. As the pin 29 of the member 30 moves in the cam groove 22, it engages the heel 28 of the switching element 23 and moves it from the dotted-line position to the full-line position shown in Fig. 1.

While the cam portion 14 is in engagement with the contact 59, the forward cam portion 15 (Fig. 1) moves into engagement with the pin 33, and the lever 31 is moved in a clockwise direction (Fig. 3). Continued rotation of the cam wheel 13 brings the member 16 into engagement with the pin 33. And, since, during this cycle of operation, the leg 65 is not in the path of the lever 31, the lever 31 is moved in a clockwise direction to the full-line position shown in Fig. 3. During the clockwise movement (Fig. 3) of the lever 31 just described, the gear 48, the shaft 41 and the plate 46 are moved, in a counterclockwise direction (Fig. 1), the distance between the control members 48 opposite Nos. 2 and 3 in Fig. 2. This brings the control member 48 at No. 3 (Fig. 2) over the contact 51 but not into engagement with it. Thereafter, during further rotation of the cam wheel 13, the adjustable member 16 and the second cam element 15, due to their shape, permit the spring 38 to move the lever 31 in a counterclockwise direction (Fig. 3) to its normal dotted-line position shown in Fig. 3. After the cam wheel finishes its cycle of rotation, the phonograph is ready to reproduce record No. 3.

While there has been described what is at present considered the preferred embodiment of the invention, it will be obvious to those skilled in the art that various changes and modifications

may be made therein without departing from the invention, and it is, therefore, aimed in the appended claims to cover all such changes and modifications as fall within the true spirit and scope of the invention.

I claim:

1. An automatic phonograph control mechanism comprising, an actuating element movable and adjustable between first and second positions, a movable assembly of manually operable control members, each of which is manually movable for independent predetermined adjustments, an electrical circuit including switch means disposed to be operated by adjusted control members, electro-mechanical means in said circuit responsive to operation of said switch means and operatively associated with said actuating element for moving said element between the first and second positions, mechanical linkage means operatively associated with said movable assembly of control members and said actuating element and movable by said element for moving each of said members successively into operative position with respect to said switch means whereby adjustments of said control members will effect adjustments of said actuating element.
2. An automatic phonograph control mechanism comprising an actuating element movable and adjustable between first and second positions, a rotatable assembly of manually operable control members, each of which is manually movable from an ineffective position to an effective position, an electrical circuit including switch means disposed to be operated by said control members, electromechanical means in said circuit responsive to operation of said switch means and operatively associated with said actuating element for operably connecting said control members and said actuating element to adjust said actuating element between the first and second positions, and means operatively associated with the actuating element and the rotatable assembly of control members for rotating the assembly and therewith the control members successively into operative relation with the switch means whereby control members in the effective position effect adjustments of said actuating element.
3. An automatic phonograph control mechanism comprising an actuating element movable and adjustable between first and second positions, a rotatable assembly of manually operable control members, each of which is manually movable from an ineffective position to an effective position, a pair of contacts disposed to be engaged by any of said control members which are in the effective position, an electrical circuit connected to said contacts and including electromechanical means operatively associated with said element and movable into engagement with said actuating element for moving said element between the first and second positions, mechanical linkage means operatively associated with said rotatable assembly of control members and said actuating element and movable by said element for rotating said members successively into operative position with respect to said first mechanical linkage means, whereby adjustments of said control members will effect adjustments of said actuating element.
4. An automatic phonograph control mechanism comprising, an actuating element movable and adjustable between first and second positions, a movable assembly of manually operable control members, each of which is manually movable for independent predetermined adjustments, electri-

cal switch means disposed to be engaged by adjusted control members, an electrical circuit connected to said switch means and including electromechanical means operatively associated with said element and movable into engagement with said actuating element for moving said element between the first and second positions, mechanical linkage means operatively associated with said movable assembly of control members and said actuating element and movable by said element for moving each of said members successively into operative position with respect to said switch means, a stop mechanism normally disposed in the path of movement of said linkage means for limiting the movement thereof to prevent rotation of said members into operative position and operatively associated with said electromechanical means to be moved thereby out of the path of said mechanical linkage only when said electromechanical means is operated and means operatively associated with said actuating element and movable thereby into engagement with said mechanical linkage means for moving it.

5. An automatic phonograph control mechanism comprising, an actuating element movable and adjustable between first and second positions, a rotatable assembly of manually operable control members, each of which is manually movable from an ineffective position to an effective position, electrical switch means disposed to be engaged by any of said control members which are in the effective position, an electrical circuit connected to said switch means and including electromechanical means operatively associated with said element and movable into engagement with said actuating element for moving said element between the first and second positions, mechanical linkage means operatively associated with said rotatable assembly of control members and said actuating element and movable for rotating said members successively into operative position with respect to said switch means, a stop mechanism normally disposed in the path of movement of said linkage means for limiting the movement thereof to prevent rotation of said members into operative position and operatively associated with said electromechanical means to be moved thereby out of the path of said mechanical linkage only when said electromechanical means is operated and means operatively associated with said actuating element and movable thereby into engagement with said mechanical linkage means for moving it.

6. An automatic phonograph control mechanism comprising, an actuating element movable and adjustable between first and second positions, a rotatable assembly of manually operable control members, each of which is manually movable from an ineffective position to an effective position, electrical switch means disposed to be engaged by any of said control members which are in the effective position, an electrical circuit connected to said switch means and including electromechanical means operatively associated with said element and movable into engagement with said actuating element for moving said element between the first and second positions, mechanical linkage means operatively associated with said rotatable assembly of control members and said actuating element and movable through a predetermined angle for rotating said members successively into operative position with respect to said switch means, a stop mechanism normally disposed in the path of movement of said linkage means for limiting the movement thereof to one-

half said predetermined angle and operatively associated with said electromechanical means to be moved thereby out of the path of said mechanical linkage only when said electromechanical means is operated and means operatively associated with said actuating element and movable thereby into engagement with said mechanical linkage means for moving it.

7. An automatic phonograph control mechanism comprising a movable cam, a cam follower operatively associated with said cam, an adjustable element pivoted to said cam for adjustment between first and second positions for controlling the action of said cam follower, a rotatable assembly of manually operable control members, each of which is manually movable from an ineffective position to an effective position, electrical switch means disposed to be engaged by any of said control members which are in the effective position, an electrical circuit connected to said switch means and including electromechanical means operatively associated with said element and movable into the path of said adjustable element for moving said element from the first to the second position, mechanical linkage means operatively associated with said rotatable assembly of control members and said cam and movable through a predetermined angle for rotating said members successively into operative position with respect to said switch means, a stop mechanism normally disposed in the path of movement of said linkage means for limiting the movement thereof to one-half said predetermined angle and operatively associated with said electromechanical means to be moved thereby out of the path of said mechanical linkage only when said electromechanical means is operated and a cam surface on said wheel movable thereby into engagement with said mechanical linkage means for moving it.

8. An automatic phonograph control mechanism comprising a movable cam wheel, a cam follower operatively associated with said wheel, a pair of cam tracks on said wheel for guiding said follower through either of two paths, an adjustable element pivoted to said wheel between said cam tracks for adjustment between first and second positions for guiding said follower into either of said cam tracks, a rotatable assembly of manually operable control members, each of which is manually movable from an ineffective position to an effective position, electrical switch means disposed to be engaged by any of said control members which are in the effective position, and electrical circuit connected to said switch means and including electromechanical means operatively associated with said element and movable into the path of said adjustable element for moving said element from the first to the second position, mechanical linkage means operatively associated with said rotatable assembly of control members and said wheel and movable through a predetermined angle for rotating said members successively into operative position with respect to said switch means, a stop mechanism normally disposed in the path of movement of said linkage means for limiting the movement thereof to one-half said predetermined angle and operatively associated with said electromechanical means to be moved thereby out of the path of said mechanical linkage only when said electromechanical means is operated and a spring-biased cam on said wheel movable thereby into engagement with said mechanical linkage means for moving it.
